UNITED STATES PATENT OFFICE.

JAMES B. OLNEY, OF BROOKLYN, NEW YORK.

IMPROVEMENT IN GAS APPARATUS FOR RAILWAY CARS.

Specification forming part of Letters Patent No. 141,886, dated August 19, 1873; application filed July 28, 1873.

To all whom it may concern:

Be it known that I, JAMES B. OLNEY, of the city of Brooklyn, county of Kings and State of New York, have invented certain Improvements in Lighting Apparatus for Railway Cars, of which the following is a specification:

This invention has for its object the lighting of railway cars by the use of the vapor of some of the well-known hydrocarbons; and the invention consists in a gas apparatus suitable for lighting railroad cars, composed of a strong vessel for holding compressed air, an automatic valve or governor for discharging the air under uniform pressure, and a carbureting apparatus, which latter is arranged in such proximity to one or more vapor-burners that condensation of vapor is avoided, while, at the same time, the heat of the burner or burners assists in vaporizing the hydrocarbon, all of which will be fully hereinafter described.

Figure 1 represents a vertical and longitudinal section of a car and two burners, with their carbureting-chambers in elevation. Fig. 2 is an enlarged view of one of the carbureting-chambers and one of the burners in section. Fig. 3 is a transverse section of the car through the pipe and valve leading from the air-chamber to the regulator or governor.

At A is represented the body of the car, near the roof of which is arranged two burners, B B', for using the vapor of any of the volatile hydrocarbons—as of petroleum, &c.—and immediately under said burners, and connected therewith, are arranged the carbureting-chambers C C', into which common air is carried from a reservoir, as at D, here shown as a box or tank underneath the car. Said box or tank is made sufficiently strong to receive and hold the air under considerable pressure, and is intended to be charged by a force-pump at some of the stations previous to the lighting of the car. From said tank or reservoir D the air is conducted, by a pipe, to a second air chamber or reservoir, shown at E, and which may be placed in any convenient location in the car. This cham-

ber is made of some flexible material, as leather or rubber, so as to open and close as a bellows; or it may be a cylinder, so arranged as to slide inside of another cylinder, as in common gas-holders, the outer one being charged with water or some fluid to serve as a packing. From this chamber E the air is conducted, by a pipe, to the carbureting-chambers C C', which are in close proximity to the burners; and there it commingles with the vapor of the hydrocarbons, and passes directly to the burner.

It will be observed that a carbureting-chamber is provided for each burner or each set of burners, if more than one be used in the same location in the car, and for the important reason that, after the air has been charged with the vapor, it will not be required to carry it any considerable distance to the burner, so that no condensation of the vapor can take place after the air is once charged. A second reason is that, where the burner is connected with the carbureting-chamber, the heat from the burner will assist in vaporizing the carbonaceous substances, and render the operation effective even in the coldest weather.

The admission of the air to the carbureter is controlled by an automatic valve at F in the pipe between the air-reservoir D and the chamber E, and said valve is connected with the movable top of the chamber E by any suitable connections, as levers and rods, so that, as the top of the chamber E sinks, the valve F will be turned to open the pipe leading from the reservoir D, and a fresh supply of air will be furnished to the chamber E, the top of which will rise and close the valve until a fresh supply of air is required.

Preventing the condensation of the vapor, and using air under great pressure, so that a sufficient quantity may be carried in a small space to last during the night, makes such an apparatus peculiarly well adapted for use upon cars; and—

I therefore claim—

1. A gas apparatus suitable for lighting railroad cars, composed of a strong vessel for holding compressed air, an automatic

valve or governor for discharging the air under uniform pressure, and a carbureting apparatus, all substantially as described.

2. The air-receiver D and governor E, having an automatic valve between them, in combination with a carbureting-chamber for operating in close connection with one or

more vapor-burners, the whole mounted upon a railway car, substantially as described, for the purpose specified.

JAMES B. OLNEY.
